CLAIM

We claim, the ornamental design for a display booth, as shown and described.

DESCRIPTION

FIG. 1 is the front perspective view of a display booth showing our new design;

FIG. 2 is a front elevation view thereof;

FIG. 3 is a rear elevation view thereof;

FIG. 4 is a side elevation view thereof;

FIG. 5 is another side elevation view thereof;

FIG. 6 is a top plan view thereof; and,

FIG. 7 is a bottom plan view thereof.

The broken lines illustrating portions of the display booth form no part of the claimed design.
